[57] CLAIM

The ornamental design for a support for cables, tubing
or the like, as described.

DESCRIPTION

FIG. 1 is a bottom plan view of a support for cables,
tubing or the like showing my design;

FIG. 2 is a top plan view thereof.

FIG. 3 is a side elevational view thereof.

FIG. 4 is a sectional view taken in the direction of the
arrows on line 4—4 of FIG. 1.
